UNITED STATES PATENT OFFICE.

CLAYTON M. JONES, OF JAMESTOWN, NEW YORK.

WRENCH.

Application filed May 20, 1922. Serial No. 562,352.

To all whom it may concern:

Be it known that I, CLAYTON M. JONES, a citizen of the United States, residing at the city of Jamestown, in the county of Chautauqua and State of New York, have invented certain new and useful Improvements in Wrenches, of which the following, taken in connection with the accompanying drawings, is a specification.

10 The invention relates to improvements in adjustable jaw wrenches for bolt nuts, and is an improvement upon the construction shown in my former Letters Patent No. 1,348,143, July 27, 1920; and the object of 15 the improvement is to provide a stronger, simpler and more easily attained construction which permits the manufacture of the wrench at a reduction in cost while attaining a stronger and more accurate assemblage 20 of the parts than in my former wrench; and the invention consists in the novel features and combinations hereinafter set forth and claimed.

In the drawings, Figure 1 is a side elevation 25 of the wrench with the jaws open to their widest adjustment showing the finished wrench with the knurled nut for adjusting the movable jaw. Fig. 2 is a rear edgewise elevation of the wrench head showing the double barrel and the slot between the barrels, the knurled nut and paneled handle being shown in dotted outline; and Fig. 3 is a front edgewise elevation of the wrench head showing the movable jaw 30 slidably mounted in the slotted wrench head and upper barrel, a part of the knurled adjusting nut showing in said upper barrel, the remainder being shown in dotted outline. Fig. 4 is a side elevation of the wrench 35 head with the side portion broken away and the knurled adjusting nut in section, showing side elevations of the partially opened movable jaw and the spiral screw rotatably fitting in the smooth lower barrel 40 to adjust the movable jaw; and Fig. 5 is a perspective view of said movable jaw. Fig. 45 5 is a perspective view of the knurled adjusting nut, showing the hole therethrough. Fig. 7 is an elevation of the adjusting screw 50 showing the round shank end upon which said adjusting nut is attached. Fig. 8 is a side elevation of a modification of the wrench head, showing the upper barrel partially closed at its rear end, thereby to strengthen 55 the fixed jaw and wrench head; and Figs. 9

and 10 show rear and front edgewise elevations of the same. Fig. 11 is a side elevation of a further modification of the wrench head showing the rear end of the lower barrel closed, the adjusting screw shortened 60 and the knurled nut attached by pinning through the screw end; and Figs. 12 and 13 show rear and front edgewise elevations of the same; and Figs. 14 and 15 are sectional views of the knurled adjusting nut 65 and a portion of the wrench head showing the different steps in the shrinking and swaging of the adjusting nut onto the adjusting screw.

Like characters of reference refer to corresponding parts in the several views.

The numeral 10 designates the wrench handle, and the numeral 11 the head portion of the wrench which has the fixed jaw 12 extending up therefrom.

The inner face of the fixed jaw 12 adjacent the head has the angular braces 13 to strengthen said jaw, said braces 13 being preferably at an angle which conforms to one side of a hexagonal nut. Said braces 80 13 extend from the fixed jaw 12 onto the wrench head 11, each side of a central slot 14.

The central slot 14 extends from the front side of the wrench head through said wrench head beneath said fixed jaw 12, opening into the upper barrel 15 crosswise of said wrench head within which slot 14 and upper barrel 15 the movable jaw 16 is slidably mounted. A second barrel 17 extends from the rear 85 side of the wrench head parallel with the barrel 15 to a crosswise opening 18 in said wrench head, which crosswise opening centers said lower barrel 17 extending equally above and below the same. The barrels 15 90 and 17 are preferably drilled from the rear side, angular extensions 19 being preferably provided on the drop forging of the wrench head to provide square faces for the drill, which angular portions 19 are cut away 100 in polishing and finishing the wrench.

Said barrels 15 and 17 are sufficiently wider than the center slot 14 and a connective slot 20 between said barrels to slidably mount the movable jaw 16 with its cylindrical extension 21 in the upper barrel 15. The rack toothed projection 22 extends down into the lower barrel through the slot 20.

A spirally threaded screw 23 rotatably fits within the smooth lower barrel 17 and is ro- 110

tatable by means of a knurled nut 24 which is preferably attached on the screw 23 in the following manner: The screw 23 is provided with a round shank 25 which fits in 5 the round hole 26 in the knurled nut 24, which knurled nut 24 is preferably reamed slightly, as shown in Figs. 14, 15 and 16, so that when said knurled nut 24 is heated and held centering the barrel 17 in the crosswise 10 opening 18 in a suitable jig, the tempered screw shank 25 may be inserted through the barrel 17 and the hole 26 in the knurled nut 24. The heat from nut 24 in turn heats shank 25 so that a few blows of a hammer 15 delivered to a punch or other suitable tool applied to the exposed end of screw 23 effects upsetting of the outer end of the shank so as to rivet and also shrink the nut 24 onto the shank upon cooling of the parts. 20 In order to assist the riveting just mentioned, the inner face of the wall 11 is concaved so as to engage the peripheral edge of the shank and expedite spreading of the metal of shank 25 upon the application of 25 the hammer blows delivered thereto. This manner of attachment also centers the screw 23 in the barrel 11 so that it rotatably fits the same and is permanently attached therein without further adjustment.

30 This simple arrangement with the smooth partial length lower barrel 17 and the above-described method of attachment for the knurled nut 24 on the shank 25 of the spiral screw 23 permits the spiral thread of the 35 screw 23 to be cut on a rod of correct size, which rod is then cut into the required length for the screw 23 and the shank 25 is then shaped, thereby providing an exceedingly accurate screw construction at low 40 cost which rotatably fits within said smooth lower barrel 17 and meshes in the rack teeth 22 on the movable jaw 16. The arrangement also closes the front end of the barrel 17 as shown in Figs. 1, 3 and 4, thereby strengthening 45 the wrench head, shutting out particles of dust and foreign matter, permitting the pleasing side paneling or countersunk effect of the handle and a portion of the head as shown in Fig. 1, thus lightening and 50 strengthening the wrench, while improving its appearance.

The modification shown in Figs. 8, 9 and 10 still further closes and strengthens the wrench head by the partial closure of the 55 rear end of the upper barrel, as shown at 27 in Figs. 8 and 9. This arrangement provides two partial length barrels 28 and 17 which simultaneously permit drilling said barrels from opposite sides of the wrench 60 head 11. The central slot 14 necessarily extends up through the closure 27, since in sawing of the slot 20 the saw can only be operated through the open end of the barrel 17. It is apparent that the closure 27 at each side 65 of the slot 14 strengthens the support of the

fixed jaw 12 on the wrench head 11, and only requires a slight reshaping of the end of the cylinder 21 of the movable jaw 16. This modified form of the closed and strengthened end of the upper barrel is preferred by many wrench users who wrongly use the rear edge of the fixed jaw 12 as a hammer to start or drive bolts or similar uses. 70

The modification shown in Figs. 11, 12 and 13 shows the full length open-ended upper barrel 15, while the lower barrel 29 is closed at its rear end 30. A modified adjusting screw 31 is inserted through the open front end of said lower barrel 29, and through the modified knurl 32 which has a larger opening therein than the preferred knurl 24. Said knurl 32 is attached to the full size shank 33 of the screw 31 preferably by a crosswise pin 34 through said knurl and shank. The end of the shank 33 preferably has the crosswise groove 35 to receive the screw driver bit to turn the screw 31 into the rack teeth 22 of the movable jaw 16, thereby attaining a good wrench, though not as strong or at as low a cost as the preferred forms of the improved wrench construction. 80 85 90 95

Figure 14 shows a further modified form of the invention in which the concavity of wall 11, is omitted. 95

As in my former wrench construction, the movable jaw 16 has an angular cut-away portion 36 on the under side of the cylindrical extension 21 so that said jaw 16 can move over the knurled adjusting nut 24 as the jaw 16 slidably moves back and forth in the wrench head 11. The diameter of the nut 24 or 32 and the cut-away portion 36 are so proportioned to each other that said cut-away portion 36 of the jaw 16 presses against the side of the adjusting nut 24 when said jaw 16 is in the extreme extended position as shown in Fig. 1, thus giving added strength to said jaw at its extreme extension when in greatest need of strength. The movable jaw 16 is preferably formed with an opposite angularly inclined brace 37 which slidably fits in the slot 14 between the braces 13 on the fixed jaw 12 and conforms to an adjacent face of a hexagonal nut to the face that is engaged by said braces 13. 100 105 110 115

What is claimed as new is:

1. The herein-described method of making wrenches which consists in forming a fixed jaw with a pair of communicating inner and outer barrels and with a transverse opening intersecting the inner barrel, and providing an outer wall the latter having a concavity, then in providing an adjustable jaw having a part fitted in the outer barrel and a rack in the inner barrel, then in heating a nut having a reamed opening and placing same in the transverse opening formed in the fixed jaw, then in inserting a 120 125 130

screw having a shank in the inner barrel and engaging same with the said rack and inserting the shank of the screw through the nut opening, and then in delivering blows to

of the transverse opening so as to upset the free end of the shank and to cause the upset part to engage in the reamed part of the nut 30 opening.

5 the outer end of the screw to cause the shank thereof to engage in the concavity of said outer wall of the transverse opening so as to upset the free end of the shank and to cause the upset part to engage in the reamed 35

10 part of the nut opening.

2. The herein-described method of making wrenches which consists in forming a fixed jaw with a pair of communicating inner and outer barrels and with a transverse opening 15 intersecting the inner barrel and providing an outer wall, then in providing an adjustable jaw having a part fitted in the outer barrel and a rack in the inner barrel, then in heating a nut having a reamed opening 20 and placing same in the transverse opening formed in the fixed jaw, then in inserting a screw having a shank in the inner barrel and engaging same with the said rack and inserting the shank of the screw through 25 the nut opening, and then in delivering blows to the outer end of the screw to cause the shank thereof to engage said outer wall

3. The herein-described method of making wrenches which consists in forming a fixed jaw with a pair of communicating inner and outer barrels and with a transverse opening 35 intersecting the inner barrel, then in providing an adjustable jaw having a part fitted in the outer barrel and a rack in the inner barrel, then in heating a nut having an opening and placing same in the trans- 40 verse opening formed in the fixed jaw, then in inserting a screw having a shank in the inner barrel and engaging same with the said rack and inserting the shank of the screw through the nut opening, and then in 45 cooling the nut to cause same to shrink onto the screw shank.

In testimony whereof I have affixed my signature in the presence of two witnesses.

CLAYTON M. JONES.
